UNITED STATES PATENT OFFICE.

GILBERT S. MARTIN, OF MYRTLE, MISSOURI.

DESIGN FOR A TOMBSTONE.

SPECIFICATION forming part of Design No. 27,418, dated July 20, 1897.

Application filed June 4, 1897. Serial No. 639,474. Term of patent 7 years.

To all whom it may concern:

Be it known that I, GILBERT S. MARTIN, a citizen of the United States, residing at Myrtle, in the county of Oregon and State of Missouri, have invented and produced a new and original Design for Tombstones, of which the following is a specification, reference being had to the accompanying drawing.

The new design is illustrated in the accompanying drawing, in which the figure represents a tombstone constructed in accordance with my invention.

The leading feature of my design consists in a tombstone having ornamental columns supported by a suitable base covered by an angular top piece and having a space between the upper portions of the columns for the reception of a plate which form sunken panels.

A represents the base of the tombstone, which is composed of the lower portion A, rectangular in general contour, the portion a', formed upon the portion a, and the upper or main portion B, resting on the base. The principal portion resting on the base is formed

of the columns b, which are, as shown, circular in cross-section and are of varying sizes from top to bottom, giving them an ornamental appearance. 25

Arranged upon the supporting-columns is the top C, composed of a cross-piece c and 30 converging pieces c', the converging pieces c' meeting at the center of the structure and forming a top to the same. The top has attached to it a cross c'', which cross may be of any of the well-known forms. Arranged between the columns is a plate D, which is of a material, such as glass, but any desired material may of course be used. 35

Having thus described my invention, what I claim is—

The design for a tombstone substantially as herein shown and described. 40

In testimony whereof I affix my signature in presence of two witnesses.

GILBERT S. MARTIN.
